UNITED STATES PATENT OFFICE.

JOHN F. PETERS, OF PITTSBURGH, PENNSYLVANIA, ASSIGNOR TO WESTINGHOUSE ELECTRIC & MANUFACTURING COMPANY, A CORPORATION OF PENNSYLVANIA.

TRANSFORMER FRAME.

Application filed December 10, 1919. Serial No. 343,971.

To all whom it may concern:

Be it known that I, JOHN F. PETERS, a citizen of the United States, and a resident of Pittsburgh, in the county of Allegheny and State of Pennsylvania, have invented a new and useful Improvement in Transformer Frames, of which the following is a specification.

My invention relates to stationary induction apparatus and it has for its object to provide means in combination with apparatus of the character designated for preventing the leakage flux therein from entering the framing of the apparatus.

15 In the accompanying drawing, Figure 1 illustrates the manner in which my invention is embodied in a transformer of the shell type; Fig. 2 is a view of a core type transformer, certain portions thereof being broken away to more clearly illustrate the manner in which my invention is embodied in apparatus of the latter character, and Figs. 3, 4 and 5 are fragmentary sectional views illustrating the damping means employed.

20 Inasmuch as the framing in stationary induction apparatus is at some point parallel to the lines of magnetic flux which circulate through the magnetic circuits of the apparatus, these lines of flux tend to leak into the framing. As the transformers increase in size, the net magnetomotive force functioning in the frame attains a large value and is often sufficiently effective to abnormally 25 heat the frame portions of the apparatus.

25 Heretofore utilized methods for preventing the flux from crowding out into the frames, such, for instance, as introducing air gaps in the frame, have proven inadequate in the larger units. Moreover, the provision of gaps in the frame members in order to preclude the establishment of a closed circuit for the leakage lines of flux often results in a weakened structure.

40 In order to overcome the obvious disadvantages of the heretofore practiced methods of preventing the leakage of the flux lines into the transformer frames, I propose to so associate damping means with the frame members that the magnetic permeance of the frame is reduced to substantially zero. Moreover, I so associate the damping means with the frame members that the maximum number of magnetic lines are embraced thereby, this specific arrangement of

the damping means being instrumental in further enhancing the beneficial results attained with my invention. As will herein-after appear, it is necessary to associate such means with only those portions of the frames which are subjected to the magnetic action.

45 Referring more particularly to the drawing, a transformer of the shell type is shown in Fig. 1 and comprises a core member 1 which is embraced by, and embraces, coil groups 2, 3 and 4, all of which are supported on pedestal legs 5-5. Horizontally extending girder members 6-6 and 7-7 serve to support the core structure in the direction 50 of its longer dimension, while end girder members 8-8 and 9-9 support the same at its ends and are secured to the members 6-6 and 7-7.

55 From a consideration of the magnetic 75 circuits of a transformer of the character described, it will be seen that the leakage lines of flux tend to crowd outwardly into the frame and there circulate, thus causing an abnormal heating of these members. In 80 order to reduce the flow of magnetic flux in the framing, I dispose thereabout, at advantageous points, short-circuited turns 10 of highly conducting material. In accordance with Lenz's law, currents will be set up 85 therein in such a direction that the damping action of the turns will substantially preclude the flow therethrough of lines of flux, it being known that it is almost impossible to cause flux to change through a 90 short-circuited turn. It will be observed that I have positioned the turns 10 at such points that they will embrace the maximum 95 number of lines of force, whereby their beneficial action is greatly enhanced.

100 Fig. 2 illustrates the manner in which my invention is embodied in a transformer of the core type. The core member in this case comprises core legs 11 and 12 and yoke members 13-13 joining the same, only the upper one of the latter being shown in the illustration. The coil members 2 and 3 are associated with the core legs 11 and 12 respectively, the coil 3 being broken away in order to show the manner in which a stiffening member 14 is positioned to support the core legs in a vertical direction. It will be understood that a companion member is positioned at the rear of the core legs shown, and that the two members together consti- 110

tute a supporting structure for the leg member. They are, however, separated from the core leg by layers of insulating material 15—15.

5 The girder members 6—6 and 7—7 are disposed along the yoke portions 13 and are secured together by frames 8 which are riveted thereto. The framing is further stiffened by the use of tie rods 16, the rod 10 which is revealed by the breaking away of a portion of the coil 3 being the only one which is substantially visible, but it will be observed that these rods pass from the top framing to the bottom framing at each of 15 the four corners of the two cruciform core legs 11 and 12, their position being indicated by the nuts which are used to increase the tension between the top and bottom framing.

Damping means 17 are associated with the 20 girders 6—6 and 7—7 and are so positioned as to embrace the maximum number of lines of force, for the purpose set forth in connection with the showing of Fig 1. The leakage lines will also tend to crowd into 25 the stiffening members 14, and I have, therefore, likewise provided that member with a short-circuited turn 18 of highly conducting material, it being observed that this turn is passed around the stiffening member and 30 occupies the space which is formed by cutting away the mid-portion of the insulating layers 15 between the stiffening member and the core leg. This construction admits of a very advantageous and beneficial positioning of the stiffening-member damping means. An additional point of leakage line 35 concentration exists, namely, the tie rods 16 and, as shown, I have wound thereabout short-circuited turns 19—19. The fragmentary sectional views, Figs. 3, 4 and 5, are 40 self-explanatory and illustrate the manner in which the short-circuiting turns are wound about the various flux-receiving frame members.

45 While I have illustrated the shell type transformer as being of a polyphase character and the core type transformer as having single-phase characteristics, it will be understood that my invention may be applied 50 to stationary induction apparatus irrespective of the phase character thereof, since I have above pointed out the specific positioning which should be used in order to realize the maximum benefits in the application of 55 my invention.

While I have illustrated but two embodiments of my invention, it will be apparent that many modifications may be made therein by those skilled in the art, and I desire, 60 therefore, that it shall be limited only by the showing of the prior art or by the scope of the appended claims.

I claim as my invention:

65 1. In a stationary induction apparatus, a core member, coils associated therewith,

framing for supporting said core member, and means comprising a short-circuited coil in combination with said framing to maintain substantially zero magnetization thereof. 70

2. In a stationary induction apparatus, a core member, coils associated therewith, framing for supporting said core member, and means in combination with said framing for reducing to substantially zero the 75 magnetization thereof by stray magnetic flux.

3. In a stationary induction apparatus, a core member and coils associated therewith, magnetizable framing for supporting said 80 core member, and damping means inductively associated with the framing for reducing to substantially zero the magnetization thereof.

4. In a stationary induction apparatus, a core member and coils associated therewith, magnetizable framing for supporting said core member, and damping means comprising short-circuited turns of conducting material inductively associated with the framing 85 for reducing to substantially zero the magnetization thereof. 90

5. In a stationary induction apparatus, a core member and coils associated therewith, magnetizable framing for supporting said core member, and damping means comprising short-circuited turns of conducting material inductively associated with the framing 95 for reducing to substantially zero the magnetization thereof, said turns being so positioned with respect to said framing as to 100 embrace the maximum number of magnetic lines of flux.

6. In a stationary induction apparatus, a core member comprising legs and yokes, coils associated therewith, magnetizable frames for supporting said core member comprising horizontally-extending girders for the yokes and vertically-extending stiffeners for the legs, and damping means for 105 reducing to substantially zero the magnetization of said girders and stiffeners. 110

7. In a stationary induction apparatus, a core member comprising legs and yokes, coils associated therewith, magnetizable frames for supporting said core member comprising horizontally-extending girders for the yokes, tension rods between said 115 girders, vertically-extending stiffeners for the legs, and damping means inductively associated with the girders, the stiffeners and the tension rods for reducing to substantially zero the magnetization of said girders and stiffeners. 120

8. In a stationary induction apparatus, a core member comprising legs and yokes, coils associated therewith, magnetizable frames for supporting said core member comprising horizontally-extending girders for the yokes, tension rods between said 125 130

girders, vertically-extending stiffeners for the legs, and damping means comprising short-circuited turns of conducting material inductively associated with the girders, the stiffeners and the tension rods for reducing to substantially zero the magnetization of said girders and stiffeners.

9. In combination with an alternating-current electrical device having a magnetizable portion subject to heating by stray magnetic flux, of a short-circuited band around said portion for substantially preventing the passage of flux therethrough.

10. An alternating-current electrical device comprising a coil, a magnetizable member 15 associated therewith and subject to heating by reason of stray magnetic flux therefrom, of a short-circuited conductor embracing said member for substantially preventing the heating of said member by preventing the 20 passage of flux therethrough.

In testimony whereof, I have hereunto subscribed my name this 25th day of November 1919.

JOHN F. PETERS.
